By his Attorney.

UNITED STATES PATENT OFFICE.

FRANK J. KOHLHAAS, OF CALUMET, MICHIGAN.

CURRENCY-HOLDER.

1,120,150.

Specification of Letters Patent.

Patented Dec. 8, 1914.

Application filed February 27, 1914. Serial No. 821,611.

To all whom it may concern:

- Be it known that I, FRANK J. KOHLHAAS, a citizen of the United States of America, residing at Calumet, in the county of 5 Houghton and State of Michigan, have invented certain new and useful Improvements in Currency-Holders, of which the following is a specification, reference being had to the accompanying drawings.
- 10 This invention relates to improvements in currency-holders and particularly to improvements in the currency-holder described and shown in United States Patent No. 986,069 granted me March 7th, 1911; and
- 15 an object of this invention is to provide a currency-holder which may readily be lengthened or shortened and which will be substantially noiseless in operation and use.
- In the drawings illustrating the principle 20 of this invention and the best mode now known to me of applying that principle, Figure 1 is a plan view of my new currency-holder; Fig. 2 is a side elevation of the same, partly in section; Fig. 3 is an end view 25 in the direction of the arrow A on Fig. 2, partly in section; and Fig. 4 is a detail which shows the follower-plate in holding position.
- The abutment-plate *a* is provided with 30 legs *b* the lower ends or feet *c* of which are shod with buffers *d* of rubber or other suitable material and in which are anchored the rear ends *e'* of the side-bars *e*. These side-bars are sectional in construction; and, 35 as is obvious from an inspection of Fig. 2, the extension-pieces *e''* may be removed by unscrewing them from one another and from the main side-bar *e* and may as readily be assembled in place in order to lengthen 40 the latter. At the front end of the currency-holder there is provided a stop-plate *f* having feet *f'* shod with buffers *f''* of rubber or other suitable material. At each of its ends this follower-plate is formed with a hole *f''* 45 through which is passed a screw-bolt *g* the threaded end of which is adapted to engage in a correspondingly threaded socket *e** with which the front end of each extension-piece *e''* and of each main side-bar *e* is formed.
- Therefore, when all the extension-pieces *e''* 50 are removed, the stop-plate *f* is fastened by the bolts *g* to the front ends of the main side-bars *e*. As in my aforesaid patent, the follower-plate *h* is provided with a pair of legs *h'* the lower ends of which are formed 55 with holes *h''*. The axes of the latter are inclined at an angle of about 10° to the axes of the side-bars *e*; and from this construction it results that the follower-plate *h* is mounted free to tilt on the side-bars *e*. 60 When the follower-plate is thrown toward the abutment-plate *a*, the follower-plate is released so that it may be slid along the side-bars toward or from the abutment-plate *a*. When the follower-plate is in holding 65 position (that is, thrown away from the abutment-plate), it is still inclined from the latter, the distance between the bases of these plates being then greater than the distance between their upper edges. The fol- 70 lower-plate *h* is provided with a finger-hold in the form of a ring *i* by which the follower-plate may be readily manipulated. Since the side-bars *e* are raised by the feet *c, f'*, above the table or other support upon 75 which the holder is normally laid, there is left between the side-bars *e* and the table a free space which permits the unimpeded tilting of the follower-plate *h*.
- I claim:
1. A currency-holder including a pair of sectional side-bars the sections of which are formed with section-engaging means by which the sections are interlocked with each other; an abutment-plate which is fastened 85 to said side-bars; a follower-plate slidably mounted on the latter; a stop-plate adapted to be fastened to the ends of said side-bars; and devices for fastening said stop-plate to said sections in turn as the side-bars are 90 built up; said fastening devices being adapted and designed to co-act with said section-engaging means.
2. A currency-holder including a pair of sectional side-bars; an abutment-plate which 95 is fastened to the same; a follower-plate slidably mounted on said side-bars; and a stop-plate fastened to the ends of said side-

bars; said abutment-plate and stop-plate being formed with feet which raise said side-bars to a height sufficient to permit the free sliding movement of said follower-plate therealong.

In testimony whereof I hereunto set my hand this twenty-first day of February

A. D. 1914, in the presence of the two undersigned witnesses at Calumet, Houghton county, Michigan.

FRANK J. KOHLHAAS.

Witnesses:

CATHERINE M. ROBERSTON,
ADA GRANT.
